UNITED STATES PATENT OFFICE.

ANDREW CHRISTIANSON, OF BUTLER, PENNSYLVANIA, ASSIGNOR TO
STANDARD STEEL CAR COMPANY, OF PITTSBURG, PENNSYLVANIA,
A CORPORATION OF PENNSYLVANIA.

PASSENGER AND LIKE CAR.

No. 854,330.

Specification of Letters Patent.

Patented May 21, 1907.

Application filed August 25, 1906. Serial No. 332,012.

To all whom it may concern:

Be it known that I, ANDREW CHRISTIANSON, a resident of Butler, in the county of Butler and State of Pennsylvania, have invented a new and useful Improvement in 5 Passenger and Like Cars, (Case 4,) and I do hereby declare the following to be a full, clear, and exact description thereof.

This invention relates to an end construction for passenger and other cars provided with end platforms and vestibules.

The object of the invention is to provide an end construction for an all metallic car which contains a minimum number of parts, and especially one of light weight.

To the accomplishment of the foregoing object the invention consists of the combination of parts hereinafter described and claimed.

20 In the accompanying drawings Figure 1 is in part an end view of the vestibule framing of a passenger car, and in part a view of the end framing of the body of the car; Fig. 2 is a vertical central longitudinal section of the 25 end framing of a passenger car embodying my invention; Fig. 3 is a side view of the frame with the finishing sheets removed; Fig. 4 is in part a horizontal section on the line 4—4 Fig. 1, and in part a plan view of 30 the framing; Figs. 5, 6, 7 and 8 are cross sections of the various door posts, and finishing plates; and Fig. 9 is a perspective view of a connecting detail at the end of the vestibule.

In the drawings the portion of the under- 35 frame shown comprises two I-beams 1, constituting center sills and extending out to the platform end or buffer sill 2, which is shown as a channel curved to the contour of the end of the car and secured directly to the center 40 sills 1. Parallel with the center sills are platform beams 3, shown as rolled channel beams extending out and secured to the platform end sill or buffer beam. The body end sill is shown at 4. This comprises a number of 45 pressed shapes, secured between the center sills and platform beams, and also extending out to the car sides, these sectional pieces being tied together by a bottom connecting plate 5, extending out to the side of the car 50 and secured to the lower flanges of the sections 4. The platform end sill or buffer beam is provided with a top cover plate 6, and a platform floor plate is shown at 7. The

steps lead down sidewise just outside of the platform beams 3 in the usual manner.

The side plates of the car body are shown at 8, these being of pressed channel shape, placed with the flanges projecting downwardly, and the outer flange being wider than the inner flange. These plates project out to the end of the vestibule, where they are connected to the vestibule end plate 9, which also is of a pressed channel shape placed with its flanges projecting upwardly and being wider at its central portion than 65 its ends and bowed both upwardly and outwardly. This end plate is connected to the side plates by knee or angle pieces 10, which are riveted to the inner vertical flange 11 of the end plate 9 and the horizontal web of the 70 side plate 8.

The body end framing comprises corner posts 13 of angle shape and just inside of these are channel shaped posts 14, the latter being pressed from plates with their outer 75 flanges wider than their inner flanges. The corner posts 13 and channel posts 14 have their upper ends secured to the webs of the side plates 8 by means of a pressed bracket 15, whose web is riveted to the angle post 13, 80 a side flange riveted to the web of the post 14, and a top flange riveted to the web of the plate 8. The channel posts 14 extend slightly above the tops of the side plates 8. The end of the body is also provided with 85 door posts 16 and intermediate posts 17, these being of pressed channel shape having flanges of different widths. These verticals are connected some distance above the floor by belt rail sections 18, which are of general 90 angle form in cross section, placed with the outer leg projecting downwardly. Near their upper ends the posts are connected by filling pieces, 19, and in line with these, between the door posts 16, is the door header 95 20, which also is of angle shape in cross section. The intermediate posts 17 extend upwardly and are secured to vertically arranged plates 21 which are in effect ventilator plates extending the full length of the car, the plates 100 shown having an out-turned flange 22 at the lower edge, and an inturned flange 23 at the upper edge, so that they constitute in effect small plate girders. The end carline of the car is composed of a lower deck section 24, an 105 upper deck section 25, and a vertical con-

necting member 26, to which the plate 21 is secured. This carline is located in the same transverse plane as the intermediate posts 16, so that a direct support for the end of the 5 roof is obtained in this manner.

The lower deck section 24 of the carline is a pressed member of general channel form having integral flanges on top and bottom edges and both ends, the flange 27 at the lower 10 end being used to secure the carline to the side frame of the car. The upper deck section 25 likewise is a pressed member of general channel form having top and bottom flanges. The vertical connecting member 26 15 is of general angle form, having a wide web, which is riveted to the vertical webs of the lower and upper deck sections of the carline, and having a flange arranged longitudinally of the car in position to receive the ventilator 20 plate 21. This construction of carline, however, is not claimed in this application, but is claimed in an application, filed August 25, 1906, Serial No. 332,014.

In line with the inner end of the lower deck 25 section, 24, of the carline is a transverse strut or beam 28, which is shown as a section of channel bar secured by means of angle pieces 29 to the intermediate posts 17, and by similar means to the upper ends of the door 30 posts 16.

The end frame of the vestibule comprises corner posts 30, end door posts 31, and a pair of intermediate posts 32 and 33. Each of 35 these is shown as formed from a pressed plate and of general channel form, having their lower ends secured to the cover plate 6 of the end buffer beam 2, and at their upper ends being connected by angle pieces 34 to the web of the end plate 9. The corner post 30 40 has its web arranged longitudinally of the car, with its inner flange substantially at right angles to the web, and its outer flange at an obtuse angle and curved as shown to conform to the end of the vestibule. The door post 31 has its inner flange at a slight 45 obtuse angle to its web, and its outer flange at an acute angle thereto, so as to bring the web of said post parallel to the center line of the car and the flanges on the curve of the 50 platform end. All of the vestibule and body end posts have the inner flanges narrower than the outer flanges, the latter serving to have riveted thereto the outer finishing 55 sheets, while the inner flanges merely form strengthening chords for the posts.

The vestibule intermediate posts 32 and 33 are connected near their bottoms as well as several places above the bottoms, by transverse members. The bottom connecting member is shown at 35, and is of general angle form having its ends bent at right angles to the body so as to form integral flanges for riveting to both the cover plate 6 of the 60 buffer beam 2 and the web of the intermediate 65

posts 32 and 33, thus serving as a means of connecting these posts to the under-frame while its upwardly projecting flange serves as a means to which the inside finishing sheets can be attached. The connecting 70 member 36 just above the angle 35 is of similar construction, but is riveted only to the intermediate posts 32 and 33. At the bottom of the end window openings of the platform is a transverse connecting member 37 forming 75 a window sill, which member is shown as of angle shape secured by angle pieces to the intermediate posts. A header for the window opening of similar construction is shown at 38. The end door header is shown at 80 40, and is of general angle form. The upper ends of the door posts 31 have connected thereto the outer ends of channel head buffer struts 41, the inner ends of which are secured to the filling pieces 19 of the body of the car. 85 In the angle between this buffer strut 41, the upper end of the door post 31, the end of the door header 40 and the end plate 9, is a casting 42, which serves as a buffer stem guide and also as a connecting member for these 90 parts, as shown in Fig. 9.

Headers for the platform side doors are shown at 44, and are of pressed channel shape, having a wider flange on the outside than on the inside, placed with their webs 95 horizontal and the flanges projecting upwardly, and being connected to the body corner posts 13 and the platform corner posts 30 by angle pieces 45.

The door openings of the body and vestibule are finished by means of pressed plates both at the sides and tops. The finishing members for the body end doors are shown at 100 50, and are of general U-shape, having the legs riveted to the inner and outer flanges of 105 the door posts 16. These members are provided with longitudinal angular indentations 51 which form a door stop. The header finishing plate 52 is of a similar construction, also having the door stop 53 pressed into the 110 same.

The door opening at the end of the vestibule is finished by U-shaped pressed plates 54, secured to the flanges of the vestibule end posts 31, and a similar header finishing plate 115 is employed.

At the corner of the body of the car is a finishing strip 56, this being a pressed plate of general U-shape, having an outer leg 57 riveted to the angle corner post 13 of the 120 body, but having the inner leg turned at right angles to normal, as shown at 58 and riveted to the outer flange of the channel post 14 of the body. This member likewise is provided with a longitudinal angular indentation 59 to 125 form a door stop. At the corner of the vestibule is a finishing strip 60, this also being a pressed plate of general U-shape, having an outer leg 61, shaped to fit against the curved obtuse outer flange of the vestibule corner 130

post 30, and having its inner leg riveted to the inner flange of the post 30. The door stop 61 is formed in part by the edges of the plate 60 and inner flange of the post 30, and in part by a pressed plate 62 riveted to the inner face of the post flange, and slightly offset, and then carried farther inwardly as at 63 to receive the inner finishing sheets 64 of the vestibule. At these side door openings are pressed headers 65 having the door stops formed therein.

By means of the special pressed shapes for posts and finishing strips, the number of parts is reduced to a minimum. Furthermore, the flanges can be made of any desired width so as to avoid the use of surplus metal wherever possible. As a consequence the weight of the construction is very greatly reduced over constructions employing standard rolled shapes and connecting pieces, and the parts also admit of an ornamental finish. The entire end construction may be of metal, although if desired both the inner and outer finish may be composition board, or even of thin wood. Preferably, however, the inner sheets will be of aluminium and the outer finishing sheets of steel.

What I claim is:

1. A metallic car post of general channel form having one flange at an acute angle to its web.
2. A metallic car post of general channel form having one flange at an obtuse angle to its web.
3. A metallic car post of general channel form having one flange at an acute angle and the other flange at an obtuse angle to its web.
4. A metallic car post formed of a pressed plate of general channel shape and having its outer flange curved and at an obtuse angle to its web.
5. A metallic car post of general channel shape having flanges of different widths and one thereof at an acute angle to its web.
6. A metallic car post of general channel shape having flanges of different widths and one thereof at an obtuse angle to its web.
7. A metallic car post formed of a pressed plate and of general channel form, having flanges of different widths, one of which is at an acute angle and the other at an obtuse angle to its web.
8. A vestibuled corner construction comprising a flanged post, a pressed plate of general U-form inclosing said post and having its limbs secured to the flanges of the post, and an angle member secured to the inner face of a flange of the post, the edge of the flange of the post and of the U shaped plate forming a door stop.
9. A metallic vestibule construction for cars comprising body corner posts, vestibule corner posts, a vestibule end plate bowed both upwardly and outwardly and secured

to the vestibule corner posts, and continuous flanged body side plates secured to the body corner posts and directly to the ends of said end plate.

10. A metallic vestibule construction for cars comprising body corner posts, vestibule corner posts, a vestibule end plate of general channel form placed with its flanges projecting upwardly, and a body side plate secured to the upper ends of the body corner posts and directly to the inner flange of the vestibule end plate.

11. A metallic vestibule construction for cars, comprising body corner posts, vestibule corner posts, a vestibule end plate secured to the vestibule corner posts, continuous flanged body side plates secured to the body corner posts and to the ends of the vestibule end plate, and a side door header secured to the body corner post and vestibule corner post.

12. A metallic vestibule construction for cars comprising body corner posts, vestibule corner posts, a body side plate comprising a channel plate with the flanges projecting downwardly and extending from the body corner posts to the vestibule corner posts, and a side door header also of channel form placed with the flanges projecting upwardly and secured to the body corner post and vestibule corner post.

13. A metallic vestibule construction for cars, comprising body corner posts, vestibule corner posts, a channel shaped side plate extending from the body corner posts to the vestibule corner posts, a channel shaped door header secured to the body corner post and the vestibule corner post, the side plate being placed with its flanges extending downwardly and the header being placed with its flanges extending upwardly and both having flanges of different widths with the wider flanges on the outside.

14. A metallic vestibule construction comprising a body corner post having a flange in the plane of the car end, a flanged post having a web transverse of the car end, a side plate over the corner post, and a bracket having a web secured to the flange of the corner post, a flange secured to the web of the flanged post and another flange secured to the side plate.

15. A metallic vestibule construction for cars, comprising vestibule end posts having webs substantially longitudinal of the car, and metallic filling pieces between said posts of flanged shape and having integral flanges at their ends secured to the webs of the posts.

16. A metallic vestibule construction for cars, comprising metallic channel end posts placed with their webs longitudinal of the car, and a filling member between said posts comprising an angle shape having its ends bent at an angle to the body to provide inter-

gral flanges which are riveted to the webs of the end posts, the horizontal flanges of said angle member being riveted to the floor structure.

5 17. A metallic vestibule construction for cars, comprising body end framing, vestibule end posts, an end plate secured to the upper ends of said posts, a hood buffer strut connecting the posts and body framing, a door header between the end posts, and a bracket secured to the ends of the door header, the buffer strut and the posts and serving to connect said parts.

18. A metallic construction for cars, comprising end posts, an end plate, a door header, and a bracket secured to said post,

plate and header and securing the same together.

19. A metallic vestibule construction for cars, comprising a body end framing, vestibule end posts, struts connecting said posts and end framing, a door header between said posts, an end plate, and a bracket secured to said post, door header, strut and end plate, and serving to connect said parts.

In testimony whereof, I, the said ANDREW CHRISTIANSON have hereunto set my hand.

ANDREW CHRISTIANSON.
